GAS OUTLET FIXTURE

Filed July 1, 1926

Patented June 14, 1927.

1,631,953

UNITED STATES PATENT OFFICE.

HORACE C. ANDERSON, OF AMARILLO, TEXAS.

GAS-OUTLET FIXTURE.

Application filed July 1, 1926. Serial No. 119,978.

The present invention relates primarily to wall outlet fixtures, and more particularly to outlet fixtures especially well adapted for use in connection with gas.

5 A primary object of the invention being to provide an improved outlet fixture embodying features whereby a flexible conductor hose may be connected with a valve mechanism normally concealed in a housing 10 disposed flush in a wall or floor.

A further object of the invention is to provide a gas outlet fixture embodying novel features of construction which render the device safe against leakage of gas due to 15 the special construction of the fixture and wherein the closure member for the fixture will be maintained in a partially opened position until movement of the valve means to a fully closed or off position.

20 A further object of the invention is to provide a gas outlet fixture embodying a valve means having an operating handle capable of being swung outwardly of the fixture housing to be readily grasped for 25 operation of the valve, and which handle when folded into the fixture housing to its fullest extent, serves as an indication that the valve is in a fully off position.

20 A still further object of the invention is to provide a gas outlet fixture which is extremely simple in operation, neat in appearance, and which is susceptible of ready installation either in a wall or a floor.

Other objects and advantages of the invention will be apparent during the course 35 of the following detailed description, taken in connection with the accompanying drawing forming a part of this specification and in which drawing:

40 Figure 1 is a face plan view of the improved outlet fixture.

Figure 2 is an enlarged face plan view showing the flush plate broken away and the valve means in a closed or off position.

45 Figure 3 is a transverse sectional view taken through the fixture, showing the same in position in a wall and showing the valve in an open position.

Figure 4 is a longitudinal section taken 50 substantially on line 4-4 of Figure 3.

Figure 5 is a fragmentary sectional view taken substantially on line 5-5 of Figure 3.

Referring to the drawing in detail, and 55 wherein similar reference characters designate corresponding parts throughout the several views, the improved outlet fixture

embodies an outlet box or housing A, a valve B provided with an operating means C, and a flush plate D for concealing of the box or housing A.

Referring to the housing A, the same preferably consists of a rectangular shaped metal box being open at the front side and embodying top and bottom walls 8, a rear wall 9, and end walls 10. While the box 60 or housing A has been shown as being of rectangular shape, the same may be square in plan if so desired.

The valve B and which is adapted to be mounted within the box A wholly inwardly 70 of the open side of the box, comprises a valve body 11 provided with a tapering valve seat 12, and extending from one side of the body 11 in right angular relation to the valve seat 12, is a threaded tubular extension 13 75 the opening of which extends to the valve seat 12. This tubular extension 13 serves as a mounting for the valve B, and is adapted to extend through an opening 14 provided in one of the end walls 10, with the shoulder 80 15 of the valve body engaging the inner face of the end wall. A clamping nut 16 threaded upon the extension 13 exteriorly of the end wall, serves for rigidly holding the valve body in its adjusted position within the 85 housing A. A gas supply pipe E is connected with the threaded tubular extension 13 as illustrated in Figure 2. It may here be stated that the valve body B is supported 90 in the housing A with the axis of the conical valve seat 12 extending parallel with the walls 8. Extending from the valve body 11, and diametrically from the extension 13, is an L-shaped extension 18 provided with a 95 forwardly extending externally ribbed nipple or stem portion 19. As will be observed in Figure 4, this stem portion 19 extends parallel with the axis of the valve seat 12 and terminates short of the open front edge 100 of the housing A. Fitting in the conical valve seat 12, is a tapering spring seated valve 20 provided with a port 21 for opening and closing of the passageways through the valve body upon rotation of the valve 20.

Projecting past the outer flat end face 22 105 of the valve 20, and preferably co-axial with the valve, is a relatively flat lug 23 and which lug co-operates for attaching of the operating means C with the valve 20. The valve 20 carries a pin 24 which co-acts with 110 stops 25 carried by the body 11 for limiting rotary movement of the valve to 90° or one

quarter of a revolution within the valve seat 12.

The operating means C for the valve B, is in the form of a handle embodying a shank portion 26 and a head portion 27. The inner end of the shank portion 26 is divided for providing spaced arms 28 which are adapted to straddle the lug 23 and be pivotally connected to the lug as by a suitable pivot pin or bolt 29. As will be observed in Figure 3, one edge of the arms 28 merges into the end edges of the arms in an arc as at 30, and which construction as will be apparent permits of the arm to be swung in but one direction from a position as illustrated in Figure 3. The head portion 27 is bifurcated for forming a pair of flaring relatively flat wings 31 and forming a substantially circular pocket 32 opening at the end of the handle. As will be observed in Figure 2, the wings 31 extend one at each side of the stem portion 19 when the handle is folded into the housing A.

Referring now to the flush plate B, and which is intended for normally concealing the housing A and valve structure B, the same embodies a substantially flat rectangular shaped body portion 35 provided with a circular opening 36. Hingedly connected at one edge to the body portion 35, as by a suitable hinge pin 37, is a disc shaped closure cap or door 38 which is provided with an inwardly bevelled edge for engaging the bevelled edge of the opening 36 when the cap is in its fully closed position. A thumb piece 39 may be provided at the edge of the cap 38 for permitting of ready opening of the cap from its fully closed position within the opening 36. It is preferred that the outer face of the cap 38 lie flush with the outer face of the body portion 35 when the cap is in its fully closed position. As will be observed in Figure 4, the pivotal connection 29 for the inner end of the handle C is spaced inwardly of the open end of the housing A past the forward terminal end of the ribbed stem portion 19.

In use, and when desiring to attach a flexible gas hose 40 to the ribbed stem portion 19, the cap or door 38 is first swung open about its pivot 37 whereupon the handle C may be swung about its pivot 29 for disposing the bifurcated head portion 27 exteriorly of the housing A and in a position to be readily grasped for operation of the valve B. The flexible gas tubing 40 may then be easily inserted over the forwardly projecting stem portion 19, and after which the handle C may be rotated for opening of the valve B. The flaring wings 31 of the head portion 27 will permit of ready and easy rotating of the valve. When desiring to conceal the valve construction, the valve B is first shut off by rotation of the handle C, and the flexible tubing 40 discon-

nected from the ribbed stem portion 19. With the valve B in an off position, the handle C may readily be swung about its pivot 29 to a position inwardly of the open edge of the housing A with the wings 31 arranged at opposite sides of the stem portion as in Figure 2. The cap 38 may then be swung closed for concealing of the entire valve means supported in the outlet box.

Should the handle C not be rotated sufficiently for completely shutting off the valve B, the relatively flat flaring wings 31 will engage the outer end of the stem portion 19 as indicated by dot and dash lines in Figure 2, and which will prevent complete closing of the hinged cap or door 38, thus informing the operator that the valve B is not completely shut off. When the valve has been fully shut off, the handle C may readily be swung to a position inwardly of the housing for permitting of complete closing of the hinged door 38. By so providing the valve B with the pin 34 and stops 25 for limiting rotary movement of the valves 20, and so pivotally connecting the operating means C to the valve, will allow for the operating means to be properly swung into the housing only at a time when the valve is completely shut off.

From the foregoing description it will be apparent that an extremely novel and efficient wall outlet fixture for gas has been provided, embodying novel safety features of construction, and embodying an operating means collapsible into the fixture in a manner for affording a neat appearing outlet fixture when not being used.

Changes in detail may be made to the specific form of the invention herein shown and described, without departing from the spirit of the invention or the scope of the following claims.

I claim:

1. An outlet fixture comprising a housing having an open side, a valve embodying a nipple portion mounted in the housing, and operating means for the valve movable into the housing only when the valve is closed.

2. An outlet fixture comprising a housing having an open side, a valve embodying a nipple portion mounted in the housing, and an operating handle for the valve movable into and from the housing only when the valve is in a closed position.

3. An outlet fixture comprising a housing having an open side, a valve embodying a nipple portion mounted in the housing, a flush plate extending across the open side of the housing and having an opening provided with a closure cap, and an operating handle for the valve movable through the opening in the flush plate only when the valve is in a closed position.

4. An outlet fixture comprising a housing having an open side, a valve embodying a

- nipple portion mounted in the housing, a flush plate extending across the open side of the housing and having an opening provided with a closure cap, and a handle pivotally connected with the valve and movable exteriorly of the flush plate thru the opening of the flush plate only after opening of the closure cap.
5. An outlet fixture comprising a housing having an open side, a valve embodying a nipple portion mounted in the housing, a flush plate arranged over the open side of the housing and having an opening provided with a closure cap, and a handle pivotally connected to the valve and having a bifurcated head portion adapted to straddle the nipple portion of the valve when the valve is in its fully off position for allowing complete closing of said closure cap.
10. An outlet fixture comprising a housing having an open side, a valve embodying a nipple portion mounted in the housing an operating handle hingedly connected with the valve and movable exteriorly of the open side of the housing, a flush plate arranged over the open side of the housing and having an opening through which the valve operating handle may project and a closure cap for the opening of the flush plate and movable to a fully closed position only after movement of the valve operating handle to a fully off position within the outlet housing.
15. An outlet fixture comprising a housing having an open side, a valve mounted in the housing and embodying a forwardly projecting nipple portion, an operating handle hingedly connected with the valve and having a bifurcated head portion forming spaced wings for straddling of the forwardly projecting nipple portion when the valve is 40 completely closed, and a flush plate embodying a closure cap, arranged over the open side of the housing for concealing of the valve and operating handle therefor.
20. An outlet fixture comprising a housing having an open side, a valve mounted in the housing by a threaded tubular extension projecting through one wall of the housing and serving as a supply pipe connection, said valve also embodying a forwardly extending nipple portion, an operating handle for the valve collapsible into the housing only after shutting off of the valve, and a flush plate having an opening provided with a closure cap, arranged over the open side 50 of the housing for concealing of the valve and operating handle.
25. An outlet fixture comprising a housing having an open side, a valve embodying a forwardly extending nipple portion, mounted in the housing, means for limiting movement of the valve through 90°, a handle pivotally connected at one end to the valve and having a bifurcated head portion providing spaced wings, said handle to be folded into the housing with the wings embracing the forwardly projecting nipple portion when the valve is in an off position, a flush plate arranged at the open side of the housing and having an opening through which the valve 55 operating handle may be swung outwardly of the housing, and a hinged closure cap for the opening in the flush plate.
30. An outlet fixture comprising a housing having an open side, a valve embodied in the housing and embodying a forwardly projecting nipple portion, an operating handle hingedly connected with the valve and having a bifurcated head portion forming spaced wings for straddling of the forwardly projecting nipple portion when the valve is 60 completely closed, and a flush plate embodying a closure cap, arranged over the open side of the housing for concealing of the valve and operating handle.
35. An outlet fixture comprising a housing having an open side, a valve embodied in the housing and embodying a forwardly projecting nipple portion, an operating handle hingedly connected with the valve and having a bifurcated head portion forming spaced wings for straddling of the forwardly projecting nipple portion when the valve is 65 completely closed, and a flush plate embodying a closure cap, arranged over the open side of the housing for concealing of the valve and operating handle.
40. An outlet fixture comprising a housing having an open side, a valve embodied in the housing and embodying a forwardly projecting nipple portion, an operating handle hingedly connected with the valve and having a bifurcated head portion forming spaced wings for straddling of the forwardly projecting nipple portion when the valve is 70 completely closed, and a flush plate embodying a closure cap, arranged over the open side of the housing for concealing of the valve and operating handle.

HORACE C. ANDERSON.
